Application July 31, 1947, Serial No. 765,002

5 Claims. (Cl. 74—70)

1

This invention relates to washing machines and more particularly to combination washers adapted to receive clothing and other fabric materials for washing or in the alternative to receive solid articles such as dishes, crockery, and the like for washing.

It is the principal purpose of the invention to provide a generally improved combination washer of the type having a tub for containing the washing liquid and in which may be received either an agitator used in washing clothing or in the alternative an impeller used in washing dishes. More specifically the invention aims to provide a unique dual drive for combination washers which is simple in construction and design and relatively economical to manufacture.

Another object is to provide a dual drive that extends upwardly into the tub of the washer through the bottom and incorporates a shaft-quill arrangement, the shaft being rotated at relatively high speed for driving an impeller and the quill being oscillated at relatively low rotational speed to drive an agitator.

Another object is to provide in a shaft-quill combination dual drive, a quill formed to interfit with an agitator to drive the latter and also formed with a circular surface for slidably engaging an impeller to guide the latter when the impeller is driven by the shaft.

Another object is to provide in a combination washer an improved basket design and construction for supporting dishes in such positions that they are efficiently washed by liquid thrown from a centrally disposed impeller.

A further object is to provide a unique drive for a dual purpose washer which incorporates a power take-off for driving a wringer. As another aspect of this feature of the invention, the drive mechanism also includes a power take-off that may be used in driving an appliance such as a rotary brush or buffer that may be used in washing and polishing pots, pans, and other cooking utensils. A still further object of the invention is to provide in a multiple purpose washer a drive mechanism enclosed in a housing for attachment as a unit to the bottom of the washing tub, such arrangement facilitating removal of the entire power unit for replacement or repair.

Other objects and advantages of the invention will become apparent from the following detailed description of a preferred embodiment, this description being made in connection with the accompanying drawings in which like parts throughout the several views are indicated by the same numerals of reference.

2

In the drawings:

Figure 1 is an elevational view partly diagrammatic showing the combination multiple purpose washer of the present invention mounted in one of the drain boards of a conventional kitchen sink;

Fig. 2 is a fragmentary top plan view of the washer and the sink, parts being broken away and removed; and this view being slightly larger in scale than Fig. 1;

Fig. 3 is a vertical sectional view with parts broken away and removed taken substantially on the line 3—3 of Fig. 2 and showing the clothes washing agitator disposed in the tub and supported on the quill to be driven by the latter;

Fig. 4 is a sectional detail through the drive housing, taken substantially on the line 4—4 of Fig. 3 and enlarged with respect to that figure;

Fig. 5 is a vertical sectional view with parts broken away and removed showing the washer converted for dishwashing purposes with the dish supporting basket assembly in place and the spray producing impeller mounted on the drive shaft therefor;

Fig. 6 is a detail plan view on an enlarged scale, showing the spray producing impeller;

Fig. 7 is a plan view of the dish supporting basket; and

Fig. 8 is a plan view of the basket tray used in combination with the dish supporting basket to hold items such as cups above the dishes.

The washing machine herein contemplated is particularly suited for use in small homes and apartments where space is limited and when it is desired to provide an inexpensive household appliance capable of being used in performing different household tasks. Although the present washer can be mounted in various types of stands and supports it is contemplated to install it in one of the drain boards of a conventional kitchen sink so that the machine will be at hand for washing dishes and the sink may be used for rinsing when clothes are being washed.

The sink has a bowl 1 on the sides of which are drain boards 2 and 3. An upright splash board 4 is disposed across the rear of the sink and along the rear edges of the drain boards 2 and 3 and may be integral with the latter. If desired, the entire sink structure including the bowl, drain boards, and splash board may be of integral construction and may be made of stainless steel or other suitable alloy. A reinforcing apron or flange 5 is formed to extend along the edge of the entire structure. A mixing faucet 6 is supported in the splash board 4 and has hot 7

3

and cold 8 valves which supply water to a swing type spigot 9. A drain 10 in the sink bowl 1 is connected to waste pipe 11.

In the drainboard 2 is a circular opening which receives the washer tub the latter having an upright cylindrical side wall 12 and a substantially flat bottom 15. The tub may be a one piece stamping with rounded bottom corners. The drainboard 2 is formed with a downwardly offset portion about the tub opening providing a narrow circular flange 16 which supports a radially outwardly directed flange 17 formed about the upper edge of the tub side wall 12. A sealing gasket 18 of rubber or cork is interposed between the flanges 16 and 17.

In the tub bottom 15 is a drain opening 19 which is connected by a conduit 20 to a T 21 in the waste pipe 11. A shut-off valve 22 is provided in the conduit 20 so that washing liquid may be either retained in the washer tub or drained therefrom as desired.

The power unit for actuating the washer is in the form of an integral assembly mounted on the tub bottom and comprises a housing structure 24 that is secured in place by screws 25 that extend through the tub bottom 15 and are threaded into bosses formed in top wall 26 of the housing. An integral guide sleeve or journal 27 is formed at one end of the top wall 26 of the housing and extends upwardly through an opening in the bottom 15 of the tub. Through the opening in the guide sleeve 27 extends a drive assembly comprising an outer tubular quill 28 and an inner shaft 29, the shaft being rotatable in the quill and guided in bushings 30 and 31. A flanged bushing 32 is interposed between the quill 28 and the guide sleeve 27.

The shaft 29 is longer than the quill 28 and extends through both ends of the latter, the lower end of the shaft continuing through the chamber in the housing, through a guide sleeve 34 in a cover 35 attached to housing bottom 36 and terminating in a coupling 37 which drivingly connects the shaft to shaft 38 of an electric drive motor 39. The motor is disposed with the shaft 38 vertical and is attached to the housing cover 35 by screws 40. Thus the motor 39, shaft 29, quill 28, and guide sleeve 27 are in coaxial relationship for rotative movement of the shaft and quill about a common vertical axis. A seal 41 surrounds the lower end of the shaft 29 and is received in a recess formed in the lower end of the guide 34 to prevent loss of lubricant along the shaft out of the housing 24.

A bevel gear 43 is secured on the shaft 29 by a pin 44 and bears on the upper end of the guide sleeve 34 to support the shaft. A sleeve 45 surrounding the shaft 29 bears on the upper end of the gear 43 and is formed at its upper end with a circular flange that engages a radial flange formed on the lower end of the bushing 31, thus serving as a support for the quill 28. An intermediate drive shaft 46 is supported horizontally for rotation within the housing 24, being journaled in integral bosses or bracket elements 47 and 48 extending into the housing chamber from the housing walls. A bevel gear 49 meshing with the bevel gear 43 is secured by a pin 50 on that end of the shaft 46 which is adjacent the vertical shaft 29. A worm 52 is secured on the other end of the intermediate shaft 46 by a pin 53 and meshes with a worm gear 54 secured adjacent the lower end of a reduced diameter portion 55 of a vertical driven shaft 56. The shaft 56 is disposed outside the tub wall 12 and extends

4

downwardly through a grease seal 47 received in a circular recess formed on the outside of a boss in the top wall 26 of the housing. A circular shoulder 58 at the juncture of the reduced diameter portion 55 and the full diameter portion of the shaft 56 bears on a washer 59 that seats in the grease seal recess and supports the shaft and the parts carried by the latter.

Rotation of the worm 52 turns the worm gear 54 and the shaft 56 at relatively low rotational speed, the shaft 46 being driven at approximately the same rotational speed as the impeller drive shaft 29 by the bevel gears 43 and 49 which are of approximately the same size.

On the lower end of the reduced diameter shaft portion 55 is secured a crank 60 which carries one end of a connecting rod 61. The other end of the rod is received on a pin in an arm 62 formed as an integral radial extension on the lower end of the quill 28. The arm 62 includes a flange portion 63 which underlies the guide sleeve 27 of the housing and limits upward movement of the quill in the sleeve. The crank 60 is of less length and throw than the quill arm 62 so that as the shaft portion 55 is rotated, the rod 61 is moved back and forth by the circular movement of the crank 60 oscillating the arm 62 over an arcuate path of about 90° to about 120° or more, but less than 180° and thereby imparting reciprocating rotative movement to the quill 28. Such rotative movements of the quill while occurring in simultaneous timed relation to the rotative movement to the shaft 29, are at a relatively slower rate of speed than that of the shaft. By reason of the speed reduction effected through the form 52 and worm gear 53 the torque imparted to the quill 28 is higher than that of the shaft 29.

The end of the intermediate shaft 46 extends through a partition 65 inside the housing and drives a small spur gear 66 mounted on the shaft. A larger gear 67 secured on a short shaft 68 meshes with the spur gear 66 and is driven by the latter at a relatively slower rotative speed. The shaft 68 is journaled in an elongated boss 69 formed in an end cover plate 70 of the housing 24. The inner end of the short shaft 68 is guided in a journal boss formed in the partition 65. Outer end 72 of the shaft 68 is formed square or non-circular in shape to receive and drive a coupling of a flexible power transmission shaft assembly, not shown. Such coupling may be held in place as by a collar screwed onto threads 73 formed on the outer end of the journal boss 69. Thus a power take-off is provided for turning a flexible shaft assembly at an intermediate rotative speed, slower than the shaft 29 and faster than the oscillatory movements of the quill 28 and the shaft 56 which, as will later appear, drives the wringer.

Clothes washing

When the washer is to be used for the purpose of washing clothing and other fabric materials an agitator A is placed in the tub and mounted on the dual drive column. The agitator comprises a central post 74 the lower portion of which is hollow and receives the quill 28. The upper end of the quill is of hexagonal or other non-circular shape as indicated at 75 and has interfitting driving connection in a similarly shaped socket formed interiorly of the post so as to establish a driving connection between the quill and the agitator.

Adjacent the upper end of the guide sleeve 27

and the quill 28 is formed with a circular sectioned guide portion 76 that is slidingly received in the lower end of the agitator post 74 to locate and stabilize the agitator in the tub and prevent lateral swaying and twisting of the agitator in use. A wide circular flange 77 is formed integrally on the bottom of the agitator post 74 and a number of upright vanes or wings 78 are disposed in the angle between the agitator post 74 and the flange 77. The agitator may be cast integrally of light material such as aluminum or of a plastic material such as a phenol formaldehyde resin.

The chamber within the agitator post 74 is extended upwardly beyond the socket portion which receives the hex-end 75 of the quill to provide a clearance chamber 80 which receives upper end 81 of the impeller drive shaft 29. The shaft end 81 is square or of other non-circular section so as to be capable of establishing a driving connection with the impeller as will later appear. Since the shaft rotates at a relatively high speed while the quill oscillates at a relatively low speed, it is essential that the shaft turn freely in the agitator. Accordingly, the chamber 80 is made of sufficient size to provide clearance between the agitator post and the shaft end 81.

A water soap solution or other washing liquid is introduced into the tub approximately to the level indicated at 82 the valve 22 being closed and the motor 39 is energized from a suitable source of electric current through a switch 83 which may be mounted on splashboard 4 of the sink structure. Clothing and other similar items to be washed are placed in the liquid in the tub and subjected to the washing action of the liquid which is moved first in one direction and then reversed by the reciprocating movements of the agitator A. A cover 84 is placed over the tub to prevent escape of washing liquid. When the washer is not in use this cover, being flat, serves as a work table or counter. The washing action of the present machine when operating with the agitator A is quite similar to that of conventional type agitator washing machines.

A wringer 85 of conventional construction and having the usual rubber covered rolls 86 and 87 is formed at one end with a depending hollow supporting post 88 which has a reduced diameter or plug end portion 89 receivable within a cylindrical socket formed in a cup 90 mounted in the drainboard of the sink. The cup journals the upper end of the vertical shaft 56 and has an outwardly directed radial flange 91 around its top, this flange being supported on a downwardly offset circular flange 92 formed in the drainboard 2. A sealing gasket 93 is disposed between the cup flange 91 and the supporting flange 92 and the parts are drawn and held together by a threaded collar 94 received on a threaded portion of the cup. A number of integral radial ribs 95 are formed in the bottom of the cup 90 and are engaged in mating notches formed in the lower end of the reduced diameter portion 89 of the wringer post 88. The interengagement between the ribs 95 of the cup and the mating notches of the wringer post hold the wringer assembly in predetermined rotative positions and prevent bodily turning of the wringer 85 with respect to the drain board. Thus the wringer is supported cantilever fashion on the post 88 and can be swung to and retained in any desired operation position, or the wringer may be removed bodily from the socket to clear the drainboard for other uses.

The wringer rolls 86 and 87 are driven through suitable mechanisms, not shown, by a shaft 96

the lower end of which is guided in a bushing 97 held by a press fit in an axial bore formed in reduced diameter or plug end portion 89 of the wringer column. The lower end of the wringer shaft 96 abuts and drivingly interfits with the upper end of the vertical shaft 56, a diametrical key 98 being formed on the latter and interfitting in a corresponding diametric slot in the shaft 96 to establish the driving connection between the shafts. In this manner the wringer rolls 86 and 87 are driven by the motor 39.

When the wringer is not in use the plug end 89 of the wringer post is lifted out of the socket of the cup 90 and the wringer is stored elsewhere.

15 In such case the socket is closed by a suitable threaded cover, not shown, threads 90 being provided in the upper end of the socket for this purpose.

Dish washing

20 The machine of the present invention can be used alternatively as either a clothes washer or a dish washer. To convert to dish washing the agitator A is removed and replaced by an impeller I (Fig. 5). This impeller which may be made by casting of a suitable light metal or plastic comprises a circular sectioned hollow hub 100 which is received over the drive column and is supported on the upper square end 81 of the shaft 29. A matching socket is provided in the upper end 25 of the hub chamber to receive the square end 81 of the drive shaft 29 so that the impeller is actuated by the latter to turn at high rotational speed such, for example, as about 800 to about 1800 R. P. M., the latter being preferable. The hollow 30 interior of the impeller hub 100 includes a chamber portion 101 sufficiently large to accommodate and provide a clearance around the hexagonal drive end 75 of the quill 28 so that the impeller may be rotated relative to the quill.

35 Adjacent the lower end of the impeller the walls of the internal hub chamber are formed to closely surround the cylindrical guide portion 76 of the quill 28 so that the impeller although turning relative to the quill is guided by the latter. 40 A metal insert bushing 102 may be cast in place in the impeller to rotate on the quill guide 76.

45 A pair of helical scoops or vanes 104 extend radially out from opposite sides of the impeller hub 103. Each of the scoops 104 is of trough-like 50 form and at the bottom of the hub terminates in a substantially straight radially extending bottom edge 105 which is disposed closely adjacent the surface of the tub bottom 15. The impeller vanes 104 may carry integral concentric partition walls 103 which form open topped channels 113 closed 55 at their upper ends. At high rotational speeds the impeller I, rotating so as to advance the radial edges 105 of the scoops into the washing liquid in the tub picks up such liquid and raises 60 it along the scoops 104 and throws it radially outward over dishes and other articles being washed. Radial holes 123 in the vanes 104 release the 65 washing liquid from the impeller scoops. For dishwashing purposes a smaller quantity of washing fluid is used than for washing clothing. For example, the washing liquid, which may be a soap solution or a water solution of any other conventional detergent, is placed in the tub up to about 70 the level indicated at 106 (Fig. 5).

Dish basket

To support the dishes and other hardware items being washed a removable basket structure B is placed in the tub over the impeller I. This basket

is composed of wire or rod elements that are preferably stainless steel or other non-rusting metal or they may be plated metal if desired. A number of peripheral rod uprights 107 are held in spaced generally parallel relation to one another by top hoop 108, intermediate hoop 109 and bottom hoop 110 to the outside of which the uprights are individually welded or soldered. The bottom ends of the uprights 107, or some of them, are curved inwardly corresponding to the contour of the tub and form supporting feet 112 of the basket. Lengths of rubber tubing 111 are frictionally received on the basket feet 112 and serve as cushions to contact the surface of the tub bottom 15. The upper ends of the uprights 107, or some of them, are curved inwardly and downwardly over the top hoop 108 providing angularly disposed guide portions 114. The ends of the guide portions 114 on the tops of the upright rods terminate in inwardly directed radial portions 115 which are welded or soldered to the underside of an inner hoop 116 of less diameter than the top hoop 108.

Within the basket B provision is made for supporting a number of dishes in several similar groups. Fig. 7, showing the plan of the basket, illustrates a novel scheme for accommodating 5 groups of dishes each comprising a series of plates of decreasing sizes. Large plate P-1 of each group is disposed obliquely across the tub and basket ahead of intermediate plate P-2, the latter being ahead of small plate P-3. The dishes are all supported in generally upright positions, the dishes of each group being one behind another and the several groups being generally radially disposed about the impeller I or central source of the cleansing spray. In each group, the several dishes are located at different distances from the spray source or impeller. For example, the intermediate dish P-2 is further away from the source than the large dish P-1 and the small dish P-3 is further still from the source of the spray liquid. This arrangement positions the relatively large or dinner plate which is apt to be the most soiled and the hardest to cleanse, relatively close to the spray source while the other plates which may be the salad and butter plates are relatively further away from the spray source.

It is also to be noted that the plane of each dish, which may be taken as the plane of the dish periphery, is disposed at an acute angle to the planes of the other dishes of the same group. This non-parallel arrangement improves the washing action and promotes the break-up and distribution of the cleansing spray as released from the impeller. Also it is to be noted that each of the dishes faces generally in a non-radial direction with respect to the center of the tub and basket.

To support the dishes in the positions shown a number of wire or rod elements are supported in the basket by cross bars 117 and 118. The cross bars 117 extend from the bottom hoop 110 in a generally radial direction to a center hoop 119 to which they are welded or soldered. The cross bars 118 extend from the bottom hoop 110 to which they are secured to an adjacent cross bar 117 to which they are also secured. The cross bars 117 and 118 are arranged in pairs, one pair for each group of dishes to be supported in the basket. The bars of each pair are somewhat divergent to accommodate the different sizes of dishes, the edges of which fit down between the cross bars. The more widely spaced parts of the

cross bars are adjacent to the large dishes corresponding to the dish P-1.

Between the cross bars are arches formed of bent wires or rods having divergent side elements 120 and 121 and top cross elements 122. The ends of the side elements of each arch are secured to the cross bars 117 and 118 so that the arches extend upwardly from the cross bars to engage the bottoms of the plates which are propped against the arches and are inclined backwardly a few degrees so that water impinging against the upper portion of the plates flows downwardly by gravity over the plate surface in a cleansing action.

15 Above the impeller I a wire mesh basket 124 is supported by upright bars 125, the lower portions of which are divergent to clear the impeller and the bottom ends of which are secured to the small hoop 119. Hoops 126 and 127 support and surround the basket 124 to protect the latter and are secured to the uprights 125. Cutlery and small items to be washed are placed in the basket 124 and receive the liquid spray directly from the top of the impeller I.

20 25 Cups, small saucers and the like are disposed on a tray structure comprising an outer hoop 128 and inner hoops 129 and 130. A number of radial bars or rods 131 are secured at their outer ends to the large hoop of the tray structure and have inner ends which are bent to provide vertical uprights 132 which are secured to the insides of the hoops 129 and 130. The interior of the tray structure is thus clear so that cutlery in the basket 124 may extend upwardly through the 30 35 hoops 129 and 130. The tray hoop 128 is of less diameter than the top hoop 118 of the basket while being of greater diameter than the small hoop 116 carried by the guide portions 114 of the basket uprights. Thus the tray structure may be supported on the guide portions 114 of the basket uprights, the tray hoop 118 interlocking or embracing the basket hoop 116 to prevent lateral displacement and tipping of the tray.

40 45 During operation as a dishwater the liquid is picked up from the bottom of the tub by the impeller I and thrown upwardly and outwardly from the vanes or scoops 104 in a helter-skelter deluge which flows over the surface of the plates and dishes stacked in the basket and cleanses the same. Some of the cleansing liquid, especially the larger droplets thereof, bounce from the surface of one dish to another so that those dish surfaces not in direct line with the spray from the impeller are washed by secondary liquid streams received from other items being washed. 50 55 There is, of course, some bouncing of the water or other cleansing liquid from the walls 12 of the tub onto the dishes and plates contained therein.

55 60 After the washing has been continued for a sufficient length of time to cleanse the dishes, the valve 22 is opened and the cleansing fluid drained out of the tub. Thereafter the washing water may be rinsed from the dishes by hot water introduced through a hand spray attached to the spigot 9 or directly from the spigot itself.

65 70 When used as a dishwasher the wringer 85 is, of course, removed and stored elsewhere and the cover 84 is used to prevent loss of cleansing liquid from the interior of the tub. Should any of the dishes be extremely difficult to cleanse or if it is desired to scour pots and pans in the sink 4, a suitable flexible shaft is attached to the power take-off shaft 68 and used to drive a rotary brush or buffing wheel.

75 80 The principles of the present invention may be

utilized in various ways, numerous modifications and alterations being contemplated, substitution of parts and changes in construction being resorted to as desired, it being understood that the apparatus shown in the drawings and described above and the particular methods set forth are given merely for purposes of explanation and illustration without intending to limit the scope of the claims to the specific details disclosed.

What we claim is:

1. Drive means for a multiple purpose washer comprising a housing, a tubular quill supported in the housing for oscillative movements about a substantially vertical axis, a shaft co-axially arranged in the tubular quill, a motor carried by the housing substantially in coaxial relation to the shaft and quill, means connecting the motor to the shaft for relatively high angular velocity rotation of the latter, means connecting the motor to the quill for relatively low angular velocity oscillation of the quill, means on adjacent ends of the tubular quill and the shaft for connecting the tubular quill to an agitator for oscillating the latter or in the alternative for connecting the shaft to an impeller for rotating the latter, and the tubular quill having a circular sectioned portion remote from said end engageable alternatively by the impeller or the agitator for guiding and laterally supporting the same.

2. In a multiple purpose washer having an agitator and an impeller interchangeable, a drive comprising a housing, a shaft journaled for rotation in the housing, a pair of concentric drive members co-axially journaled in the housing one for rotation and another for oscillation about an axis disposed at an angle to the shaft, a driving connection between the shaft and one of the drive members for oscillating the latter, a driving connection between the shaft and the other of the drive members for simultaneous rotation thereof, and a motor directly connected to one of the concentric drive members to actuate the latter at the same rotational speed as the motor.

3. In a multiple purpose washer having an agitator and an impeller interchangeable, a drive comprising a housing, a shaft journaled for rotation in the housing, a pair of concentric drive members co-axially journaled in the housing one for rotation and another for oscillation about an axis disposed at an angle to the shaft, a driving connection between the shaft and one of the drive members for oscillating the latter at a relatively slow angular velocity, a driving connection between the shaft and the other of the drive mem-

bers for simultaneous rotation thereof at a relatively high angular velocity, and a motor directly connected to one of the concentric drive members to actuate the latter at the same rotational speed as the motor.

4. In a multiple purpose washer having an agitator and an impeller interchangeable, a drive comprising a housing, a shaft journaled for rotation in the housing, a pair of concentric drive members co-axially journaled in the housing one for rotation and another for oscillation about an axis disposed at an angle to the shaft, a driving connection between the shaft and the outer drive member for oscillating the latter, a driving connection between the shaft and the inner drive member for simultaneous rotation thereof, and a motor directly connected to one of the concentric drive members to actuate the latter at the same rotational speed as the motor.

5. In a multiple purpose washer having an agitator and an impeller interchangeable, a drive comprising a housing, a shaft journaled for rotation in the housing, a pair of concentric drive members co-axially journaled in the housing one for rotation and another for oscillation about an axis disposed at an angle to the shaft, a driving connection between the shaft and the outer drive member for oscillating the latter at a relatively slow angular velocity, a driving connection between the shaft and the inner drive member for simultaneous rotation thereof at a relatively high angular velocity, and a motor directly connected to one of the concentric drive members to actuate the latter at the same rotational speed as the motor.
